UNITED STATES PATENT OFFICE

ALTON E. COBB, OF LOS ANGELES, CALIFORNIA

FLUSH TANK

Application filed July 30, 1931. Serial No. 554,052.

This invention relates to flush tanks.

An object of the invention is to provide a flush tank having an inlet and an outlet, with the outlet controlled by a valve. Means is provided for holding the outlet valve open, after having been opened, and an object of the present invention is to provide a novel construction for causing the holding means or trip to release the outlet valve and permit it to close after it has been held open a period of time.

Another object of the invention is to provide a flush tank construction wherein the parts are relatively simple and durable, for accomplishing the desired function of the construction.

With the foregoing and other objects in view, which will be made manifest in the following detailed description, and specifically pointed out in the appended claims, reference is had to the accompanying drawings for an illustrative embodiment of the invention, wherein:

Fig. 1 is a sectional view through the improved flush tank.

Fig. 2 is a sectional view taken substantially upon the line 2—2 upon Figure 1.

Fig. 3 is a partial view on an enlarged scale, illustrating a detail of construction.

Fig. 4 is a horizontal section taken substantially upon the line 4—4 upon Figure 3.

Fig. 5 is a horizontal section taken substantially upon the line 5—5 upon Figure 2.

Referring to the accompanying drawings, wherein similar reference characters designate similar parts throughout, the improved flush tank consists of a tank 10, shown as being rectangular in form although the shape is immaterial. This tank has a closed top and an open bottom which is normally closed by a bottom closure 11 bolted or otherwise secured thereto as by bolts 12. An inlet pipe 13 leads into the tank and is provided with a T 14 discharging into the tank. A pipe 15 leads from the T up through an elbow 16 to a needle valve 17, the needle of which is adjusted by an adjusting rod 18 which extends through between closure 11 and which is provided with a handle 19. From the

needle valve there is a standpipe 20 leading

upwardly to a point adjacent the top of the tank and having a downwardly directed outlet 21. An operating tank 22 has brackets 23 which are slideable on the standpipe 20 and this operating tank has its open top positioned beneath outlet 21. In its bottom there is an outlet 24 having a downwardly closing check valve 25. A rod 26 extends through the bottom closure 11 and may have its upper end adjusted by rotating handle 27. This stem like rod 18 is threaded through the bottom closure. The upper end of the rod extends into the outlet 24 so as to be capable of engaging the under side of valve 25 when the operating tank lowers, so that on lowering the operating tank its outlet valve 25 will be opened by rod 26. A lever 28 is pivoted on a yoke 29 which is vertically adjusted on standpipe 20 and a link 30 connects this lever to the operating tank. Lever 28 is also connected to a counterbalance weight 31 which is slightly heavier than the weight of the operating tank when the operating tank is empty. Counterbalance weight 31 is connected to a lever 32 which is pivoted on an arm 33 of a support 34 which may be mounted on bottom closure 11. This support has pivoted thereto a trip 35. Trip 35 has its downward movement arrested by arm 33 but can be swung upwardly about its pivot when engaged by pawl 36 pivoted as at 37 on lever 32. Downward movement of this pawl is limited by a stop 38. The support 34 is so positioned and trip 35 is so positioned as to be engageable by the outlet valve 39 controlling the outlet 40 leading from the flush tank. Outlet 40 has connected thereto a fitting 41 in which a crank 42 is rotatable. This crank is rotatable by a handle 43 and carries a connecting rod 44 which is connected by a link 45 to the outlet valve 39. Outlet 40 is materially larger in diameter than the inlet provided by T 14.

The operation and advantages of the improved flush tank are as follows. Inlet pipe 13 is connected to a suitable source of water supply. The level of water in the tank indicated at 46 is established by the pressure of the entrapped air in the top of the tank becoming equal to the pressure of water in

inlet pipe 13. When the handle 43 is rotated, this rotates crank 42 lifting valve 39 into the dotted line position shown in Figure 2. As the valve swings through its arc it encounters trip 35, lifts the trip and permits the trip to drop past the edge of the valve coming to rest on arm 33. When the handle is released, valve 39 encounters the trip and is held in the dotted line position. This permits water in the flush tank to pass out through outlet 40. Of course, as soon as water starts flowing through the outlet, additional water is being supplied to the tank through T 14 but as the outlet from the tank is larger than the inlet, the water level in the tank will gradually lower. The water in the operating tank 22 is entrapped therein when the tank is in the position shown in Figure 1. Consequently as the water level 46 on the outside of the operating tank lowers, the weight of water entrapped in the operating tank cooperates with the weight of the tank to overbalance the counterbalance weight. This moves the counterbalance weight 31 upwardly with the result that pawl 36 passes over the trip and assumes a position beneath it. As the operating tank slides down on standpipe 20, its outlet valve 25 encounters rod 26 and is opened by it permitting water in the operating tank to flow out and reducing the combined weight of the operating tank and contained water. When the combined weight is sufficiently reduced, the counterbalance weight 31 becomes effective to overbalance the operating tank and contents. This swings lever 32 and causes pawl 36 to lift trip 35, releasing valve 39 and permitting it to close. When the valve 39 is closed water continues to flow into the tank until an equilibrium of conditions is established, returning the water level 46 to the elevation as shown. The operating tank 22 is refilled by water discharging through outlet 21. The downward movement of the operating tank is limited by engagement of the lower bracket 23 with collar 29, although any other suitable stop construction may be provided for limiting this movement.

From the above described construction it will be appreciated that a novel, simple and durable, flush tank has been provided.

It will be noted that all of the operating structure is mounted on the bottom closure 11 permitting the bottom closure, with associated apparatus, to be readily installed within a tank 10. In the event that any part should get out of order or require replacement, tank 10 can be easily removed which exposes the entire construction, making it quite easy to repair or replace any parts. The flow through the standpipe 20 and through the outlet 21 for refilling the operating tank 22 is adjusted by adjusting the needle valve.

Various changes may be made in the details of construction without departing from

the spirit or scope of the invention as defined by the appended claims.

I claim:

1. A flush tank comprising a tank having an inlet and an outlet, a valve controlling the outlet, a trip for holding the valve open after having been opened, an operating tank movable in said tank adapted to be filled with liquid, a counterbalance weight counterbalancing the operating tank and causing it to assume an upper position when surrounded by water in the tank, means operable by the counterbalance weight to cause the trip to release the valve and permit the valve to close when the level of water in the tank lowers producing a lowering of the operating tank, and means for opening the operating tank to discharge its contents when lowered due to the fall of liquid level in the tank.

2. A flush tank comprising a tank having an inlet and an outlet, a valve controlling the outlet, a trip for holding the valve open after having been opened, means engageable with the trip for causing the trip to release the valve, means for operating said means comprising an operating tank having a valve controlled outlet and a counterbalance weight, and means for opening the valve controlled outlet of the operating tank when it is lowered by the lowering of the liquid level in the tank.

In testimony whereof I have signed my name to this specification.

ALTON E. COBB.
